UNITED STATES PATENT OFFICE.

CHARLES HENRY WURST, OF QUINCY, ILLINOIS.

STOVE.

1,035,067.

Specification of Letters Patent.

Patented Aug. 6, 1912.

Application filed November 9, 1911. Serial No. 659,396.

To all whom it may concern:

Be it known that I, CHARLES HENRY WURST, a citizen of the United States, residing at Quincy, in the county of Adams 5 and State of Illinois, have invented certain new and useful Improvements in Stoves; and I do hereby declare the following to be a full, clear, and exact description of the invention, such as will enable others skilled 10 in the art to which it appertains to make and use the same.

This invention relates to stoves and more particularly to the construction of the lower part of the same.

15 An object of the invention is to form the main portion of the base and the ash box integral, with air passages between the base and the ash box and to provide an upper part for the base to direct air between the 20 outer casing of the stove and the fire-pot or combustion chamber.

A further object is to provide a base especially adapted for use in connection with stoves of the type to which my co-pending 25 application, Serial Number 654,591 relates.

Other objects and advantages will be hereinafter set forth and pointed out in the specification and claim.

In the accompanying drawings which are 30 made a part of this application, Figure 1, is a top plan view of the improved form of base, Fig. 2, is a bottom plan view thereof, Fig. 3, is a vertical sectional view on the line 3—3, Fig. 1, Fig. 4, is a similar view at 35 right angles to Fig. 3, taken on the line 4—4 of Fig. 1, Fig. 5, is a view similar to Fig. 1, the upper detachable portion of the base being removed, and, Fig. 6, is a bottom plan view of the removable upper plate of the 40 base.

Referring more particularly to the drawings in which similar reference numerals designate corresponding parts throughout the several views, 1 represents the lower or 45 main portion of the base which may be square or of any preferred form and has its lower edge 2 flared outwardly to rest upon a floor or support upon the floor. The sides of the base 1 are preferably vertical and extending inwardly from the upper edge of 50 three of the sides are connecting straps 3, to the opposite ends of which is connected the plate 4 forming the top of the ash box 5, said ash box 5 depending from the plate 4, 55 within the base 1, as will be clearly seen by referring to the drawings. The connecting

straps 3 may be of such size as to have their inner ends connected with the upper portion of the ash box 5, as well as with the plate 4, if desired. The straps 3 are suitably spaced from one another and are preferably located at the corners and suitable distances between the corners, the corner straps 3 having suitable bolt openings 6 extending vertically therethrough. The purpose of these 60 openings will later appear. The fourth side of the base 1 and the corresponding side of the ash box 5 are cut away and the same are provided with a suitable opening 7 through which the ash box may be readily cleaned 65 of its contents and which is adapted to be closed by a suitable door (not shown). This side will hereafter be termed the front side. The central portion of the plate 4 is raised and provided with the large circular opening 8 from which depend the right angled 70 grate supporting arms 9 for supporting the grate immediately above the ash-pot. The upper circular edge 10 of the plate 4 is enlarged and provided in its upper face with 75 the circular groove 11 to receive the lower edge of a fire-pot of any suitable construction. The front portion of the plate 4 is also raised to a plane slightly below that of the upper circular edge 10. The raised 80 front portion is indicated by the numeral 12 and is provided with the arc shaped flange 13 extending upwardly therefrom, slightly forwardly of the upper curved or circular edge 10 of the ash box. The raised front 85 portion 12 has the long straight front edge 14 and the short side edges 15 which are connected with the long front edge 14 by the short forward portion 16 and with the raised central portion of the plate 4 by the short 90 straight connecting edges 17. The side edges 15 are positioned at angles of about 45 degrees to the short connecting portions 16 and 17 and if continued, would meet at about the center of the circular opening 8. 95 At suitable points along the side edges 15 are located the enlargements 18 through which the vertical bolt passages 19 extend to accommodate the bolts (not shown), the purpose of which will be later stated. A suitable 100 opening 20 is provided through the raised front portion 12 to allow air directed downwardly through any suitable down-draft throat, having its lower edge secured around the opening 20, to enter the ash box 110 5 for upward travel through the grate of the stove, as will be clearly understood.

The outer portion of the upper edge of the base 1 is cut away to form the seat 21 around the back and sides of the base and this seat is continued along the edges 15 of the front raised portion 12. The purpose of this seat is to accommodate the removable top section 22 of the base, the edges of the section 22 resting upon the seat 21, and being flush with the upper surface of the upper raised portion 12. Suitable bolts 23 are passed through openings provided therefor in the section 22 and through the bolt openings 6 and 19. Suitable nuts 24 are secured upon the threaded ends of the bolts 23 and thus 15 the top section 22 is securely fastened in position upon the base 1. The section 22 is of such form as to rest a short distance above the straps 3 and the air passages between said straps and the central portion of said 20 section is cut away to provide a central opening somewhat larger than the upper circular edge 10 of the ash box 5. The front portion of the section 22 is also cut away to correspond with the upper raised portion 12, 25 the cut away portion of the front of the section 22 being of the same size and form as the front raised portion 12 of the top plate 4, the converging edges 25 fit against the edges 15 and the short straight edges 26 and 30 27 connecting with the edges 25 which engage against the short straight edges 16 and 17 respectively, when the top section 22 is in position upon the base 1. Carried upon the inner face of the top section 22 and located at suitable distances along the three 35 sides thereof are the fingers 28 which depend slightly below the lower edge of said section and engage against the inner face of the corresponding sides of the base 1, adjacent the upper edge thereof. The fingers 28 serve to securely hold the top section 22 in proper position and prevent movement thereof after said section has been placed upon the base 1. Near the inner circular 40 45 edge 29 of the top section 22, is the upwardly directed flange 30 projecting from the upper face of the section and connecting with the flange 13 upon the raised front portion 12 to form the complete circular flange, which is adapted to rest against the 50 circular outer casing (not shown) of the next section of the stove. The casing of the stove fits against the face of the flange toward the upper circular edge 10 of the ash 55 box plate 4 and may be held in position by bolts or other suitable securing means (not shown) passed therethrough and through the perforated ears 31 extending upwardly from the flange 30. The top section 22 is 60 preferably provided with a rigid bracket arm 32 projecting from one front corner thereof and having a suitable perforation 33 which assumes a position directly above the hinge opening 34 within the flared lower 65 edge 2 of the base 1. The purpose of this

perforated bracket arm 32 and the opening 34 therebeneath is to accommodate a hinge pin upon which the door to the ash box may be hingedly carried. It will thus be seen that the upper section 22 co-operates with the 70 upper edge 10 of the plate 4, serving to hold the next section of the stove in proper position above the base 1. It will also be evident that as the central opening in the upper section 22 is of a diameter somewhat 75 greater than that of the upper circular edge 10, the air directed upwardly between the base 1 and the ash box 5 will be allowed to circulate from the front corners of the base or rather from one short edge 17, around the 80 circular upper edge 10 to the other edge 17 and then upwardly between the outer casing, resting against the flanges 13 and 30 and the fire-pot, the lower edge of which rests within the groove 11. Between the 85 casing and fire-pot the air may be thoroughly heated to be later utilized for heating the room or compartment within which the stove is situated.

It will be evident that the base 1 may be 90 positioned upon any suitable support to allow the free circulation of air therebeneath so that the same may readily find its way between the base 1 and the ash-box 5 to travel upwardly therebetween through 95 the air heating chamber or chambers provided between the fire-pot and the outer casing of the stove. It will also be apparent that a portion of the air after being heated between the fire-pot and stove casing, may be directed downwardly through any suitable form of down draft throat and through the opening in the raised front portion 12 of the plate 4 to enter the ash box 5 and travel upwardly through the grate 100 supported upon the right angled grate supporting arms 9. As the fire-pot, casing and down draft form no part of this invention, however, and may be of any suitable type, it has been deemed unnecessary to illustrate 110 the same in this application.

This improved form of base and ash box, formed of two pieces may be employed in connection with stoves of various types and will be highly efficient and effective in the 115 performance of its duties.

It will thus be seen that I have produced a combined stove base and ash box of improved type and which may be employed to support the upper sections of stoves of various types. It will also be evident that this form of two part combined stove base and ash box may be manufactured at a small cost, thus greatly reducing the cost of manufacturing and marketing the stove, employing 120 this form of combined base and ash box.

What I claim is:

A device of the class described comprising a stove base, an ash box within said base and spaced therefrom, spaced straps formed 130

integral with said base and box, and connecting the upper edges thereof, a top for said box having a central opening therein, a portion of said top between the front of said box and said opening being raised and provided with a second opening, a removable plate positioned over said base and spaced from said top and having an opening therein of greater diameter than the opening in said top, said plate being cut

away to receive the raised portion of said top, and means for securing said parts together.

In testimony whereof I have signed my name to this specification in the presence of 15 two subscribing witnesses.

CHARLES HENRY WURST.
